[57] CLAIM

The ornamental design for an electrode pad for electrocardiograph, substantially as shown and described.

DESCRIPTION

FIG. 1 is a top plan view of an electrode pad for electrocardiograph showing our new design;

FIG. 2 is a side edge view thereof;

FIG. 3 is a rear edge view thereof;

FIG. 4 is a front edge view thereof;

FIG. 5 is a top perspective view thereof;

FIG. 6 is a bottom perspective view thereof.

FIG.1

FIG.2

FIG. 3

FIG. 4

FIG.5

FIG.6
